UNITED STATES PATENT OFFICE.

FRANK DAVIS, JR., OF DUQUOIN, ILLINOIS, ASSIGNOR OF ONE-HALF TO WESLEY H. MENG, OF DUQUOIN, ILLINOIS.

SPARK-PLUG.

1,177,998.

Specification of Letters Patent.

Patented Apr. 4, 1916.

Application filed May 4, 1915. Serial No. 25,787.

To all whom it may concern:

Be it known that I, FRANK DAVIS, Jr., a citizen of the United States of America, residing at Duquoin, in the county of Perry 5 and State of Illinois, have invented new and useful Improvements in Spark-Plugs, of which the following is a specification.

This invention relates to certain novel and useful improvements in spark plugs 10 for hydrocarbon engines.

In carrying out the present invention, it is my purpose to provide a spark plug wherein the sparking terminals of the plug will be automatically cleaned on each up 15 stroke of the engine piston, thereby preventing the accumulation of carbon at the contact points and insuring the proper working of the plug.

It is also my purpose to provide a spark 20 plug wherein the sparking terminals of the electrodes will be in axial alinement with each other and equipped with a fan-shaped cleaning device rotatably mounted thereon and adapted to be revolved and moved longitudinally during certain strokes of the 25 engine piston with the effect to thoroughly clean the sparking terminals and remove any carbon or foreign matter therefrom.

With the above and other objects in view, 30 the invention consists in the construction, combination and arrangement of parts hereinafter set forth in and falling within the scope of the claim.

In the accompanying drawing, Figure 1 35 is a view in side elevation of a spark plug constructed in accordance with the present invention. Fig. 2 is an enlarged fragmentary longitudinal sectional view therethrough. Fig. 3 is a transverse sectional view through the same.

Referring now to the drawing in detail, 40 1 designates a spark plug which, in the present instance, embodies an outer metal casing 2 having one end externally screwthreaded 45 to engage the threads on the wall of the opening in the engine cylinder, and an electrode holder 3 disposed within the casing 2 and suitably secured therein and carrying the power electrode, the holder 3 being 50 formed of porcelain or other suitable insulating material, as usual.

In accordance with my present invention,

a ground electrode 4 of substantially U-shape has one limb secured to the cylinder end of the casing 2 and the remaining limb 55 disposed in axial alinement with the power electrode 5 carried by the electrode holder 3. The limb of the U-shaped ground electrode 4 alining with the power electrode 5 is formed, adjacent to the central section of 60 such ground electrode, with a shoulder 6, and rotatably mounted upon the limb of the ground electrode alining with the power electrode is a hub 7 from which radiate fan blades 8.

In practice, the pressure developed in the engine cylinder on each up stroke of the piston acts upon the fan blades 8 to rotate the latter and the hub 7 and move the hub 7 and the fan blades longitudinally along the 70 alining electrodes. In this rotary and longitudinal movement of the hub 7 and fan blades the contact points are thoroughly and effectively cleaned, thereby removing carbon and other foreign matter from the 75 points and maintaining the same in good working order.

While I have herein shown and described the preferred form of my invention by way of illustration, I wish it to be understood 80 that I do not limit or confine myself to the precise details of construction herein described and delineated, as modification and variation may be made within the scope of the claim without departing from the spirit 85 of the invention.

I claim:

A spark plug for hydro-carbon engines comprising a power electrode and a U-shaped ground electrode having one leg 90 thereof alining axially with the power electrode and formed with a shoulder, a hub rotatably mounted upon said leg of the ground electrode and resting upon said shoulder and blades radiating from said 95 hub substantially as and for the purpose described.

In testimony whereof I affix my signature in presence of two witnesses.

FRANK DAVIS, JR.
